UNITED STATES PATENT OFFICE.

PAUL S. SHOAFF, OF AKRON, OHIO, ASSIGNOR TO THE GOODYEAR TIRE & RUBBER COMPANY, OF AKRON, OHIO, A CORPORATION OF OHIO.

APPARATUS FOR MARKING MATERIALS.

Application filed April 17, 1926. Serial No. 102,677.

My invention relates to a method of and a machine for handling sheet materials of various size or quality and it is particularly directed to a method of identifying their exact 5 classes.

One object of my invention is to facilitate the manipulation of assembly parts in an article of manufacture.

Another object of the invention is to provide means for identifying various classes of assembly units.

More specifically, this invention affords a flexible means for distinguishing rubberized fabrics which are to be used in building various articles of manufacture, and provides a marking medium to be employed in so distinguishing the articles.

In the rubber industry, particularly in the manufacture of tires, it is necessary to handle a large number of sizes and grades of materials. Thus, each tire may embody several types of fabrics, each of which is impregnated with a rubber stock which has characteristic compounding ingredients. It is necessary, during the assembling of these units, to quickly, yet accurately, distinguish the various fabrics and compounds.

In the past this has been accomplished by carefully separating each class of goods. However, where several sizes and qualities of tires are being continuously manufactured, it becomes increasingly inconvenient to practice this method efficiently.

Another method, which has been employed, is to weave a tinted cord into the fabric and, by noting its particular color, the class of the article is readily ascertainable. This method, however, requires a great deal of time to locate the key cord before ascertaining its color. Moreover, it necessitates a large stock of fabric having the necessary colors and, in addition, does not provide for the use of the various compounding ingredients which may be applied to the same grade of fabric.

My invention consists generally in passing calendered fabric over spaced discs which have been wetted with a colored marking fluid. With the aid of this mark, I am able 50 to readily distinguish both the fabric and the compound employed thereon. It is apparent that this method provides for three degrees of freedom; namely, the color or combination of colors, the distances between

the marking rollers and the design of the 55 mark, each of which may be easily varied by changing the color of the marking medium and changing or respacing the distances between the marking discs.

For a better understanding of my invention reference may be made to the accompanying drawings, in which:

Fig. 1 is a front elevation of a double unit, portions being broken away for clearness, showing a wetting roll within a fluid container;

Fig. 2 is a side elevation of a double unit showing opposite ends, one unit being in removed and the other in engaged position;

Fig. 3 is a detail view, on a larger scale, of a journal for gear train shown.

In practising my invention I employ a machine consisting of a frame provided with suitable upright end members 1 and a horizontal brace 2 adapted to hold the members in position. Mounted in the end members are a plurality of upright guides 3, upon which supporting members 4 of a marking mechanism 4^a are slidably mounted.

In order to maintain the supporting members of the marking mechanism in operative or inoperative position, a counter-weight mechanism has been provided. Such mechanism consists of a horizontally disposed shaft 6 which is journaled in the frame, and is provided at one end with a bell crank lever 7 rigidly secured thereto at the outside of the frame members 1. Also a plurality of bifurcated arms 8 are spaced from the ends 9 of, and are rigidly secured to, the shaft 6 inside the frame members 1. One arm of the lever supports an adjustable counterweight 9 and the other arm 10 thereof may be employed for the manual manipulation of the device. The adjustment of the counterweight 9 is effected by merely sliding it in either direction along the arm to which it is loosely secured, or a set screw 9^a or other similar device is adapted to secure the weight 100 in adjusted position. The bifurcated ends of the arms 8 are each provided with a roller 12, rotatably mounted within the fork and adapted to engage the base of the supports 4. The force from the lever moment is transmitted through the shaft 6 to the arms and is thus directed to oppose the weight of the marking device. It is to be noted that the

moment arms of the counterweight and the arms 8 change sufficiently, when shifted from an engaging to a removed relationship, to insure that the support will remain in the desired position.

The marking means include a plurality of discs 29, adapted to carry a suitable marking fluid upon their peripheries, and a fluid container 17. The marking means are supported by a plurality of pins 15 rigidly connected to the ends of the container and resting in grooves 16 especially provided therefor in the vertically slideable supporting members 4.

The container is preferably of semi-circular metallic construction and it should have a length substantially equal to the width of the fabric. Near the bottom thereof a drain tap 18 is provided, which may be employed to maintain the fluid at substantially a constant level. Brackets 19 are riveted to the ends of the container 17 and, as shown in Figure 3, they constitute supports for the lower sections of bearings 20 and bosses 21. The upper collar sections of the respective journal bearings 20, differ in that the one, 24, is made an integral part of a vertically disposed journal support 22 for a gear train 23 composed of gears 23^a and 23^b journaled upon stud shafts 23^c and 23^d, respectively secured to the supports 22. Since, however, only one gear train is essential for each marking unit the other collar section 26 is similar to the section 24, but is without provision for the gear train support 22. Both are fitted with bosses 21 through which bolts 31 pass vertically upward to support bearing sections 25 similar to those shown at 26. The bolt is provided with nuts 31^a on the outer sides of the bosses in order to hold the sections in position.

The upper bearings 25 journal a horizontal shaft 27 keyed at one end to a gear 28 which forms part of the train 23. A plurality of discs 29 are each rigidly mounted on the shaft 27 by means of a set screw 30. The discs serve to mark fabric as it passes tangent to their peripheries and beneath an idler roller 29^a that is mounted upon brackets 34 secured upon the end members. The rotary motion imparted to the discs by rolling contact with the fabric is transmitted through the gear train to a wetting roller 32, having oppositely disposed bearing portions 32^a rotatably mounted in the bearings 20, one of the bearing portions being rigidly connected to the bottom gear 33.

It should be noted, of course, that the distance between the discs may be varied to meet the demands of the process by merely loosening the set screws 30 and sliding the discs along the shafts 27. It should also be observed that a plurality of colored fluids may be employed to give a greater degree of flexibility. For example in Fig. 2 it is pos-

sible to provide the two fluid containers with different coloring mediums; it is also possible to operate the units selectively or simultaneously.

By partially submerging the wetting roller 70 in the marking fluid within the container, a sufficient amount thereof adheres to the periphery of the roller to wet the periphery of the discs.

While the character of the marking fluid 75 is not important, it is desirable that it consist of such ingredients as are not apt to cake or solidify. I have found that a suitable white printing fluid may be made by mixing lithopone with latex, which has been 80 made slightly alkaline. The desired consistency may be produced by adding a pine oil dispersion of rubber to which some gum arabic and water has been added. A red marking fluid may likewise be obtained by 85 substituting red oxide for lithopone. In each case, the components are thoroughly mixed, preferably in a paint mill of any regular construction. It is to be noted that the marking fluid consists preferably of a 90 pigment, latex and a material which will give the fluid a proper consistency. It is desirable for the fluid to possess certain properties as, for example, chemical inertness and non-volatility. In addition it must 95 give a tacky surface when dry in order that fabric will adhere thereto.

It will be apparent to anyone skilled in the art that by practising my invention it is possible to easily distinguish the many 100 grades of fabric commonly utilized in the manufacture of tires. Moreover, this is accomplished without multiplying the steps of manufacture inasmuch as the device may be installed in any convenient juxtaposed position to calendering equipment.

Although I have illustrated and described but a single device embodying my invention, it is evident that the principle thereof may be subjected to wide variations without departing from the scope thereof, and I desire, therefore, that only such limitations shall be imposed as are in accord with the appended claims.

What I claim is:

1. A machine for marking rubberized fabric comprising a supporting frame adapted to be positioned adjacent a moving sheet of fabric, means mounted in the frame for applying an identifying mark to the fabric, means associated with the frame for moving the marking means into contact with the sheet, and means associated with the marking means for supplying a marking fluid thereto.
2. A machine for marking rubberized fabric comprising a frame adapted to be mounted adjacent the face of a traveling sheet of fabric, marking discs rotatably mounted within the frame, means asso-

ciated with the marking discs to move the latter into and out of contact with the fabric, and a roller mounted in the frame for applying marking fluid to the discs.

5. A machine for marking rubberized fabric comprising a frame adapted to be mounted adjacent the face of a traveling sheet of fabric, supporting members mounted within the frame, a horizontal shaft carried by the supporting members, marking discs axially adjustable upon the shaft, means for supplying marking fluid to the discs and means for moving the supporting members toward and away from the fabric 10 to cause the discs to engage or disengage the latter.

4. A marking device comprising a frame adapted to be mounted beneath a traveling sheet of fabric, a vertically adjustable marking mechanism slidably mounted with respect to the frame, means for elevating the mechanism to cause it to contact with a sheet of material including a horizontal shaft carrying rigidly mounted arms supporting the mechanism and a bell crank lever connected to the shaft and provided with a counter-weight for balancing the weight of the marking mechanism.

5. A ply marking device comprising a supporting frame, a marking disc mounted for radial displacement in said frame, a counter weighted mechanism for moving said disc, and a wetting roll mounted upon means maintaining it in contact with the

disc at all times for transferring marking fluid thereto. 35

6. A ply marking device including a rigid frame provided with a counter-weighted elevating mechanism, a plurality of ply marking discs and a fluid container carried by the mechanism, and a wetting roller mounted in the container and engaging the discs. 40

7. A ply marking device comprising a frame, marking mechanism so positioned in the frame as to contact with a ply adjacent thereto, a lever mechanism for elevating the marking mechanism including a shaft journaled in the frame having a plurality of arms provided with rollers for supporting 45 the marking mechanism and a second arm provided with a weight for balancing the weight of the marking mechanism. 50

8. A ply marking device comprising a frame adapted to be mounted beneath a traveling sheet of fabric, an elevating mechanism comprising a shaft journaled in the frame, arms rigidly secured to the shaft, rollers rotatably mounted upon the arms, a balancing lever rigidly secured to the shaft, a counter-weight mounted upon the arms and a marking mechanism supported upon the rollers and adapted to be moved by the latter into and out of contact with the fabric. 55 60 65

In witness whereof, I have hereunto signed my name.

PAUL S. SHOAFF.
